UNITED STATES PATENT OFFICE.

RICHARD E. JONES, OF PEARL RIVER, NEW YORK, ASSIGNOR TO DEXTER FOLDER COMPANY, OF PEARL RIVER, NEW YORK, A CORPORATION OF NEW YORK.

SHEET-SEPARATING MECHANISM FOR PAPER-FEEDING MACHINES.

1,063,037.

Specification of Letters Patent.

Patented May 27, 1913.

Application filed March 29, 1912. Serial No. 887,071.

To all whom it may concern:

Be it known that I, RICHARD E. JONES, a citizen of the United States, residing at Pearl River, county of Rockland, and State 5 of New York, have invented certain new and useful Improvements in Sheet-Separating Mechanisms for Paper-Feeding Machines, of which the following is a specification.

10 This invention relates more especially to vacuum sheet separating mechanisms for machines which feed sheets of paper and the like, and has for its primary object to provide in a device of this character improved 15 means for maintaining sufficient suction in the cylinder of the apparatus while said cylinder is being raised bodily to lift a portion of the sheet to be fed.

A further object is to provide an improved snapper operating with the suction apparatus in preventing the feed of more than one sheet at a time.

Toward the attainment of these objects and others, which will appear in the specification and be specifically pointed out in the appended claims, my invention contemplates an improved construction, combination and arrangement of parts exemplified in the drawings in an adaptation for feeding sheets of cardboard and the like.

In the drawings, Figure 1 is a side elevation of a sheet separating device embodying my improvements; Fig. 2 is a similar view showing the parts in different positions; Fig. 3 is a rear elevation of the same; Fig. 4 is a top plan view of the same; Fig. 5 is a detailed elevation of portions of the device, the suction cylinder being shown in section and in raised position; Fig. 6 is 35 a fragmentary side elevation of the same; Fig. 7 is a fragmentary top plan view of the suction cylinder with portions of its support.

Referring more particularly to the drawings, this embodiment of my invention is for the most part supported from a bracket arm 1, which may be secured to a rigid portion of an adjacent frame or other suitable support. A guide block 2 is adjustably secured by a bolt 3 to the bracket arm 1. Within the guide block 2 is adjustably mounted a slide 4, provided at its upper end with a threaded boss 5 for the reception of an adjusting screw 6, which is journaled in the upper end of the guide block 2. A support-

ing apron or plate 7 is integrally rigidly formed with the slide 4 and is provided with a bearing 8 upon a cam shaft 9 to be again referred to. Reciprocably mounted within a pair of band sockets 9 at the rear edge of the apron 7 is a pump cylinder 10, within which reciprocates a piston 11 on the lower end of a rod 12, which is connected by a link 13 with one arm of a cam lever 14, said cam lever being pivoted on a pin 15 carried by the apron 5' which projects laterally from the boss 5 at the upper end of the slide 4. A cam link 16 which is pivotally connected at 17 with the lever 14, is provided with a cam roller 18 adjacent its lower end, which rides 60 on a cam 19 secured to the cam shaft 9. A spring rod 20 is pivotally connected at 21 with the forward end of the lever 14, a spring 22 being mounted on the rod 20 between its pivot 21 and an abutment 23 to 65 maintain the roller 18 in engagement with the cam 19. On the lower end of the cylinder 10 is carried a sucker 24, which is open to the interior of the cylinder 10. A band 26 is clamped to the outer wall of the 70 cylinder 10, a connecting link 27 connecting it to one arm of a cylinder operating lever 28, which is pivoted on a pin 29, which is also carried by the apron 5'. A link 30 which has its upper end pivotally connected 75 at 31 with the lever 28 is provided adjacent its lower end with a cam roller 32, which rides a cam 33. For holding this cam roller against its cam a spring rod 34 has its upper end pivotally connected at 35 with the other 80 arm of the lever 28 and carries a spring 36 in abutment with the plate 23.

A snapper device to be used in the manner hereinafter pointed out, comprises a presser foot 37 depending from a connecting block 85 38, which is slidably mounted upon a horizontal rod 39. As shown in Fig. 4, said presser foot 37 is carried by the depending extremity of an L-shaped rod 40, which is releasably held in adjusted position in the block 38 by means of a set screw 41. The rear end of the rod 39 is secured to one end of a short bar 42, which is pivoted immediately of its ends at 43 in a depending bracket 44. The other end of said bar is 100 pivoted at 45 to the curved lower end of a connecting rod 46, the upper end of which has an adjustable end 47 with a longitudinal slot 48, within which reciprocates a pin 49 carried by a lever 50. A spring 51 carried 105

by the spring rod 52 with its upper end sliding in a spring abutment 53, shown in dotted lines in Fig. 3, is pivotally connected at 54 at its lower end with the bar 42. By 5 these means the foot 37 is normally held against the stack 55 of sheets, which are carried by a feed table of any suitable description. In order to adapt the presser foot 37 to be raised at certain periods of 10 the operation the lever 50 is pivotally mounted at 56 on the apron 7. A cam roller 57, carried by the lever 50, rides a cam 58 on the cam shaft 9. A spring rod 59, which is pivoted at 60 with one end of 15 the lever carries a spring 61 between its pivot 60 and the abutment 23 to hold the cam roller 57 in engagement with the cam 58. On the lower end of a depending bracket arm 62 is pivoted at 63 a clamping 20 foot 64. In order to raise and lower said foot at certain intervals, a rod 65 is pivoted at 66 to the clamping foot 64, the upper end of the rod 65 being adjustably connected with one end of the lever 50 in the manner 25 shown best in Figs. 1 and 2. A stack retaining finger 66', which projects laterally from an irregular link 67 is pressed down on to the stack of sheets 55 by means of a spring (not shown on the drawings) which 30 is mounted on the rod 68 between adjustable abutments 69. This retaining finger 66' is thus maintained in this position during the operation of the machine. In order to maintain the connecting links 16 and 30 in 35 proper position with respect to the cams 19 and 33 the lower ends of said links are provided with suitable yokes, which straddle the cam shaft 9. Said cam shaft 9 is journaled at its outer end in a boss 70 carried by 40 the outer end of a bracket 71. A universal coupling 72 serves to connect the cam shaft 9 with a driving sleeve 73 with which it is extensibly connected.

The operation of my improved device will 45 now be readily understood and briefly stated is as follows: When the parts are in the positions shown in Figs. 1 and 3 the presser foot 37 is held to the stack 55 by the compression spring 51. At the same time, the 50 sucker 24 is pressed against the uppermost sheet of the stack by reason of the cylinder being in its lowermost position. As the cam 19 revolves with the shaft 9, the cam roller 18 by means of the link 16 raises the 55 lever 14 into the position shown in Fig. 2 causing the piston 11 to partially exhaust the cylinder 10 and sealing the top sheet to the sucker 24. As the cam 33 forces the lever 28 upwardly, the cylinder 10 is raised, 60 the top sheet being lifted in the manner indicated in Figs. 3, 5 and 6. Shortly previous to this action however, the cam 58 has raised the lever 50, which lifts the clamping foot or presser finger 64 while at the same 65 time permitting the spring 51 to force the

presser foot 37 down on to the stack 55. Shortly after the piston and the cylinder have begun their upward movements, cam 58 drops from under the roller 57, permitting the compression spring 61 to overcome 70 the compression spring 51, causing the lever 50 to drop and to press the lever 64 down on to the next sheet underneath. At the same time the presser foot 37 is rapidly lifted and the sheet is then suitably disposed to be completely separated from the stack 75 55 by a blast of air or any other suitable means. An inspection of Figs. 1 and 2 will show that shortly after the sheet has thus been completely segregated from the stock 80 55, the cam 19 permits the lever 14 to drop to disengage the lifted sheet from the sucker 24. The action of the cam 33, however, continues for a longer period to permit the sheet to be drawn from the stack. 85

What I claim is:

1. In a device of the character described, an apron, a cylinder reciprocably mounted adjacent one edge of said apron, a piston in said cylinder, a lever for reciprocating said cylinder, another lever for reciprocating said piston, and pivots for said levers projecting laterally, from said apron. 90

2. In a device of the character described, an apron, a cylinder reciprocably mounted on said apron, a lever pivotally mounted on a part rigid with said apron, and operably connected to said cylinder, a piston in said cylinder, a lever pivoted on a part rigid with said apron for reciprocating said piston within said cylinder, and means for adjusting the position of said apron. 95

3. A sheet separator for feeding machines, comprising a vacuum cylinder provided with a sheet gripping sucker, a piston in said cylinder, means for lifting said cylinder, means for moving said piston to exhaust the air in said cylinder, said piston moving means being operative before the cylinder lifting means and continuing during and after the 105 lifting movement of said cylinder and a snapper comprising a presser foot impinging the stack prior to the movement of said piston and releasing its hold at approximately the initiation of the cylinder lifting 110 movement. 115

4. In a sheet separator and feeding machine, a vertically adjustable apron, a cylinder reciprocably mounted on said apron, a cylinder reciprocating lever pivoted on said 120 apron, a piston in said cylinder, a piston reciprocating lever pivoted on said apron, a presser foot for a pile of sheets, an operating lever therefor pivoted on said apron, and a cam shaft journaled in said apron and having cams mounted thereon for respectively operating said levers. 125

5. In a sheet separator for feeding machines, a sheet lifting device, a presser foot normally pressed against a stack of sheets, 130

a clamping foot, and an actuating lever positively connected to said clamping foot, said lever being provided with a lost motion connection with said presser foot, whereby said 5 presser foot is raised approximately at the limit of the downward movement of said clamping foot.

6. In a sheet separator and feeding machine, a vertically adjustable apron, a cylinder reciprocably mounted on said apron, a cylinder reciprocating lever pivoted on said apron, a piston in said cylinder, a piston reciprocating lever pivoted on said apron, a presser foot for a pile of sheets, an operating 10 lever therefor pivoted on said apron, a cam shaft journaled in said apron and having cams mounted thereon for respectively operating said levers, and a lost motion connection between said presser foot and the 15 presser foot operating lever.

7. In a sheet separator for feeding machines, the combination of a cylinder, a piston movable therein, a sucker carried by said cylinder, a clamping foot, a cam movement 20 for raising and lowering said cylinder, a second cam movement for reciprocating said piston therein during its movement, a third cam movement for raising said clamping 25

foot at the beginning of the upward movement of said cylinder, a presser foot normally impinging the top sheet of a stack from which sheets are to be fed, and a rod 30 connecting said presser foot with the cam movement for operating said clamping foot, said rod having a pin and slot connection 35 with said cam movement to permit relative differential movement between said clamping foot and presser foot.

8. In a sheet separator for feeding machines, the combination with a sheet lifting device, of means for raising and lowering said device, a clamping foot, an operating lever positively connected to said clamping foot, a presser foot operating bar pivoted intermediately of its ends, a presser foot 40 mounted thereon on one side of its pivot, and a connecting link connected to said operating bar on the other side of said pivot, said connecting link being provided with a pin and slot connection with the lever which 45 operates the clamping foot.
